UNITED STATES PATENT OFFICE.

JAMES THOMPSON, OF GREELEY, COLORADO.

DEVICE FOR GRADING AND PACKAGING ARTICLES ACCORDING TO SIZE.

Application filed October 10, 1924. Serial No. 742,882.

To all whom it may concern:

Be it known that I, JAMES THOMPSON, a citizen of the United States of America, residing at Greeley, in the county of Weld and State of Colorado, have invented certain new and useful Improvements in Devices for Grading and Packing Articles According to Size, of which the following is a specification.

10 This invention relates to devices for use in assorting or grading articles according to size and, while especially valuable for use in grading fruits and vegetables, could be used for many other purposes, such as the screening of coal, ores, etc. The article will be described herein as used for grading potatoes.

20 The principal object of the invention is to provide an efficient combination of sorting chains which will increase the efficiency of the machine, the ease of operation, and the simplicity and economy of manufacture thereof.

25 Another object is to construct a sorting chain which can be easily manufactured, which will readily travel around drums or sprockets, and which present a maximum area of measuring openings.

30 A further object is to provide means in a device of this character for adjusting the angle of travel of the chains so that the time the articles remain on the chains may be controlled.

35 A still further object is to so construct the driving drums of the chains that they may be adjusted to suit chains of various pitches and meshes.

40 Other objects and advantages reside in the detail construction of the invention, which result in simplicity, economy, and efficiency and which will become more apparent from the following description.

45 In the following detailed description of the invention, reference is had to the accompanying drawings which form a part hereof. Like numerals refer to like parts in all views of the drawings and throughout the description.

In the drawings:—

50 Fig. 1 is a side elevation of the invention looking in the direction of the arrow "1", Fig. 5.

55 Fig. 2 is a vertical cross section through the device, taken on the line 2—2, Fig. 1.

60 Fig. 3 is a detail cross section through the chain drive rollers of the device.

Fig. 4 is a longitudinal section through the drive roller taken on the line 4—4, Fig. 3.

Fig. 5 is a plan view of the complete 60 device.

Fig. 6 is a detail view of the sorting chain.

Fig. 7 is a detail view illustrating the method of attaching the chain bars together. This view is taken on the line 7—7, Fig. 6. 65

The invention comprises a supporting frame 10 in which is hung a sorting frame 11. The sorting frame 11 is horizontally pivoted at its forward extremity, as shown at 12, to the supporting frame 10. The rearward extremity of the sorting frame hangs on hangers 13 which connect at their upper extremities with arms 14 carried secured on a horizontal shaft 15. A hand lever 16 is also carried by the shaft 15, which co-acts 70 with a sector 17 on the frame 10 to hold the shaft 15 in any desired position. The elevation of the free extremity of the sorting frame 11 is controlled by the lever 16.

75 Journaled on the sorting frame 11, are an upper and lower drive shaft, numbered 18 and 19 respectively, and an upper and lower idler shaft, numbered 20 and 21 respectively. The drive shafts 18 and 19 are positively connected together by means of 80 a sprocket chain 22 and a sprocket carried by each of said shafts. One extremity of the drive shaft 18 is provided with an operating crank 23 and the opposite extremity of the drive shaft 19 is provided with a 85 similar operating crank 24. The cranks 23 and 24 are used for hand operation of the machine. Should it be desired to operate by power, the cranks would be replaced by a belt pulley or chain sprocket. 90

95 An endless sorting chain, which will be hereinafter designated the second sorting chain 25, passes around a drive drum 26, secured on the drive shaft 19 and around an idle drum 27, carried by the idler 100 shaft 21.

105 A similar sorting chain of larger mesh, which will be hereinafter designated the first sorting chain 28, passes over a drive drum 29, secured to the upper drive shaft 18; over an idler drum 30, carried on the upper idler shaft 20; under an idler drum 31, carried by the lower idler shaft 21 and thence over an idler drum 32, carried on the lower drive shaft 19, back to the drive 110 drum 29.

It can be readily seen the operation of

the hand cranks 23 and 24 will cause both the sorting chains 25 and 28 to travel in the same direction over their respective drums. In use, the upper portions of the chains travel rearward toward their drive drums as indicated by the arrows in Fig. 1.

Carried on the forward end of the supporting frame 10 is a hopper 33 which directs the potatoes onto the forward portion 10 of the first sorting chain 28. A chute 34 is arranged to receive potatoes from the discharge end of the first sorting chain and carry them into a bag 35 which is carried on suitable bag holders 36 at the rear of 15 the machine.

An angularly disposed longitudinal chute 37 extends between the drive drum 29 and the idler 30, under the upper portion of 20 the first sorting chain 28, and serves to convey the potatoes which pass through the chain 28, to the second sorting chain 25. This chain, being of smaller mesh, will retain a portion of the potatoes delivered to it (called "seconds") and convey them to a 25 chute 38 which deposits them in a bag 58 carried by suitable bag holders 59. The very small potatoes of no commercial value and the dirt and clods pass through the second sorting chain 25 to the ground.

30 Side boards 39 and 40 are arranged along the chain 28 to retain the potatoes thereon.

Should it be found that "seconds" are being carried over by the first sorting chain to the chute 34, the lever 16 is used to raise 35 the end of the sorting frame so that the potatoes must be carried up an incline. This incline causes the stream of potatoes on the chain to have a tendency to roll backward and assists in agitating them so that 40 the fall of the "seconds" and clods will be facilitated.

The machine is usually placed on skids and drawn along the rows in the field. The 45 lever 16 here serves to level up the sorting frame when the machine stands on inclined ground.

The sorting chains 25 and 28 are of unusual and novel construction and comprise 50 a series of alternately-facing, bent rods 41 held together by loop-shaped clips 42. It will be noted that co-acting bends in the rods 41 form substantially square openings 43 for the sifting of the articles. The size of 55 the openings 43 determines the classification of the product.

The distance from one clip 42, along the axis of the chain, to the next clip 42 determines the mesh of the chain. It will be 60 noted, however, that each mesh has a hinge point at its center so that the chain will bend at each one-half mesh point. This is an unusually flexible construction for a chain of this character. The chain can be very 65 easily manufactured since there are only two parts—the rods 41 and the clips 42,

and all rods in the same mesh chain are identical. The chain rides over the drum on the clips 42 which present a broad wearing surface.

In order to provide means for adjusting 70 the machine to receive chains of varying meshes, the drive rollers 26 and 29 are of special and novel construction. They comprise a pair of disks 44 carrying webs 45.

The disks 44 are secured to the drive shafts 75 and connected by L-shaped blades 46, which are secured to the webs 45 by means of bolts 47 which pass through slotted openings 48 in the blades. The angularly turned portions of the blades form the drum surface 80 for the support of the sorting chain. Secured along the radial faces of the blades 46 are adjustable teeth 49. The teeth 49 are secured to the blades 46 by means of bolts 50 which are adjustable in slotted openings 85 51 in the blades. Should it be desired to adjust the drum for a chain of larger mesh, the blades are moved outward on the webs 45 until the circumferential distance between the adjacent teeth equals the pitch or mesh 90 of the chain. The bolts 47 are then tightened. The teeth 49 are now adjusted along the blades until they register with the clips 42 of the chain and the drum is ready for use.

95 The bag holders 36 and 59 are carried on a cross bar 54 secured to the frame 10 as shown at 55, so that they remain stationary as the sorting frame 11 is adjusted.

The chutes 34 and 38, which carry the 100 potatoes to the bags are of telescopic construction and comprise an upper section 52 which is secured to the sorting frame 11, and a lower co-acting section 53 which is secured to the supporting frame 10. By this construction, the chutes are allowed to 105 lengthen or shorten as the sorting frame is raised or lowered.

110 There are two sets of the bag holders 36 arranged to support two bags 35 at the same time. This construction allows one of the bags to be filling while the other is being replaced or removed. Hinged in the chute 34, as shown at 57, is a gate 56 which can be 115 actuated to direct the stream of potatoes into either of the bags 35.

120 While a specific form of the improvement has been described and illustrated herein, it is desired and understood that the same may be varied, within the scope of the appended claims, without departing from the spirit of the invention.

Having thus described the invention, what I claim and desire secured by Letters Patent is:—

125 1. A sorting machine comprising, a supporting frame; a sorting frame within said supporting frame; a plurality of sorting chains carried in said sorting frame; a pivot for supporting one extremity of said sorting frame from said supporting frame and

means for raising or lowering the other extremity thereof above and below said pivot.

2. A sorting machine comprising a supporting frame; a pivoted sorting frame within said supporting frame; a plurality of longitudinally disposed sorting chains of differing mesh carried in said sorting frame and means for conveying the material which passes through each of said chains onto the surface of the chain of next smaller mesh in combination with means for varying the vertical angle of travel of all said chains simultaneously so that said chains will travel at an upward or downward angle as desired.
3. A sorting chain comprising a series of connected, similar bent bars, each of said bars comprising a plurality of straight, equal, angularly-extending, alternately-parallel, sections separated by straight, relatively short, parallel, sections and terminating at each extremity in straight, similar, similarly-extending, end sections, each of the latter sections being placed at an angle of 90° to said short, parallel, sections, all portions of each of said sections lying in the same plane.

4. In a sorting machine having a supporting frame, a sorting frame hinged to said supporting frame at its one extremity; a plurality of endless, adjacently-placed sorting chains carried in said sorting frame; a rotatable bell-crank lever carried on said supporting frame and means for supporting the other extremity of said sorting frame from one leg of said lever said lever having a throw which will cause said chains to travel at an upward or downward angle as desired.

5. A sorting machine comprising two endless, traveling, sorting, chains; two upper parallel shafts and two lower parallel shafts, one of said chains being passed around all four of said shafts the other chain being passed around the two lower parallel shafts only, so that the upper reaches of the chains will be at different elevations while the lower reaches are at the same elevation and means for conveying material from below the uppermost reach to the top of the second chain.

In testimony whereof, I affix my signature.

JAMES THOMPSON.
